UNITED STATES PATENT OFFICE.

JOHN EDWARD LEE, OF CHICAGO, ILLINOIS.

EMBROIDERY-ENVELOPE.

SPECIFICATION forming part of Letters Patent No. 324,854, dated August 25, 1885.

Application filed April 12, 1884. (No model.)

To all whom it may concern:

Be it known that I, JOHN EDWARD LEE, a citizen of the United States, residing at Chicago, in the county of Cook and State of Illinois, have invented certain new and useful Improvements in Embroidery-Envelopes for Packing Embroidery, Laces, and Similar Goods, of which the following is a specification.

10 The object of my invention is to provide a very simple and easily-constructed envelope in which the embroidery, lace, or other goods can be easily packed, effectively displayed for sale, readily withdrawn when required, and 15 protected from dust or injury when packed away.

My package consists of an envelope with a flap broad enough to cover, or nearly cover, the body of the envelope in which the goods are 20 packed, and with the inside sheet of the pocket cut through, leaving an opening for the display of the goods. When the goods are not being shown, the flap is folded down, covering the opening in the pocket and the goods completely. At one end of the envelope, in the same sheet with the larger opening, I cut a small slit a short distance from the opening referred to. This slit is for the purpose of 25 allowing the goods to be withdrawn, to cut off 30 and sell, or for use.

My invention will be best understood by referring to the drawings, in which—

Figure 1 is a perspective view of my invention. The flap is shown thrown back, the 35 goods in place, and one end slightly drawn out. Fig. 2 is a plan view of the sheet for forming the envelope opened out.

A is the inside sheet of pocket or body of envelope. B is the flap; C, the goods; D, slit 40 for allowing the goods to be withdrawn.

E is the back of pocket; H H, small flaps for gumming to back E to form pocket of en-

velope; f f, line of fold of upper face of pocket upon back; e e, line of fold of flap of envelope. Broken lines are folding-lines of sheet.

45 This envelope consists of a single strip of paper with the width of the length of the completed envelope, and in length about equal to three times the width of the finished article. About one-third of the length of the sheet of 50 paper is then folded over an equal portion of the sheet, to form a pocket having its opening for the insertion of its contents at the inner edge. The remaining portion of the sheet is then folded down as a flap—that is, the part 55 A is folded over upon E to form the pocket, and B acts as the flap. The inside of pocket A has two openings cut in it, the larger one for the display of the goods C, and the smaller, D, for their withdrawal for use or for sale, as 60 may be.

This envelope may be made of any suitable material, though I prefer to use paper, and any words or devices may be printed upon any part of it.

65 The goods are inserted folded, but not carded, into the pocket of the envelope, and when not required for inspection the flap is folded down.

Having now fully described my invention, 70 what I claim, and desire to secure by Letters Patent, is—

An envelope for packing embroidery, made of one piece and consisting of a pocket and a flap, the pocket having an opening for the display of the goods, and a slot for withdrawing the goods without disturbing the folds, substantially as shown and described.

75 In witness whereof I have hereunto set my hand.

JOHN EDWARD LEE.
